ROLLABLE SOUND-PRODUCING TOY

Earl B. Swebilius, Hamden, Conn.

Application December 17, 1948, Serial No. 65,801

6 Claims. (Cl. 46—114)

1

The present invention relates to improvements in toys and relates more particularly to improvements in toys of the type which are rollable and which produce sound.

As will be apparent from the accompanying drawings, considered in conjunction with the following description, the present invention contemplates a combination in which there is provided a roller-member in conjunction with a yoke eccentrically connected to the roller-member in such manner that sound is produced for the amusement and entertainment of children, if not for their parents.

I am aware that prior to the present invention rolling toys embodying a roller-member and a yoke have been provided (see U. S. Patents 741,963; 1,234,472; and 1,523,929) and that eccentric rolling-members have also been provided eccentrically connected to a body to produce a rolling motion (see U. S. Patent 1,681,666). No one prior to the present invention, so far as I have been able to ascertain, has ever perceived that by combining the yoke of the prior art with eccentric connections to a roller-member, sound could be produced for the amusement of children, without resorting to complex, costly or delicate mechanisms.

One of the main objects of the present invention is to provide a superior toy of the character referred to which will appeal both visually and audibly to children and attract their interest by odd and intriguing movements of the toy in its sound-producing gyrations.

Another object of the present invention is to provide a rollable sound-producing toy which combines low cost for manufacture with both eye and ear appeal, as far as children are concerned.

A further object of the present invention is to provide a superior toy of the character referred to which will withstand hard usage, and in the event of bending or the like, may be readily restored to substantially normal condition.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a top or plan view of a preferred form of rollable sound-producing toy embodying the present invention;

Fig. 2 is an edge view thereof;

Fig. 3 is a view of the toy in front elevation with the outer end of the handle-unit omitted;

2

Fig. 4 is a broken sectional view taken through the roller-member and its bearing-connection to the yoke;

Fig. 5 is a transverse sectional view taken on the line 5—5 of Fig. 2;

Fig. 6 is a perspective view of the handle-unit; and

Fig. 7 is a perspective view of one of the tires prior to its application to the roller-member.

The preferred form of toy embodying the present invention and illustrated in the accompanying drawings, includes a roller-member generally designated by the reference character 10 and a handle-unit generally designated by the reference character 11.

The roller-member 10 above referred to is of drum-like form and includes a tubular body 12 and two complemental end-plates 13 and 14 respectively crimped or otherwise secured to the opposite ends of the said body 12. The end-plates 13 and 14 are of circular form and respectively struck inwardly to provide bearing-cuffs 15 and 16 for purposes as will hereinafter appear. Both of the bearing-cuffs 15 and 16 are eccentrically located with respect to the center of the respective end-plates 13 and 14 and are preferably located diametrically opposite each other, as is especially well shown in Fig. 4.

Encircling the tubular body 12 of the roller-member 10 are two tires 17—17 respectively located adjacent the opposite ends of the said body and of sufficient thickness to maintain the periphery of the tubular body 12 out of contact with the floor or other surface when the toy is being rolled thereon in a manner as will hereinafter appear. Preferably, the tires 17—17 are formed from flat rings of rubber or other elastic material similar to the rings employed for sealing fruit jars and the like, and having a normal internal diameter (Fig. 7) considerably less than the diameter of the tubular body 12 upon which it is desired to install them. When a flat ring such as is shown in Fig. 7 is stretched over the body 12, it will, due to such stretching, lie flat thereon.

The handle-unit 11 before referred to comprises a substantially U-shaped yoke generally designated by the reference character 18 and having a cross-reach 19. From the opposite ends of the said cross-reach project two integral parallel side-arms 20 and 21, which are spaced from each other a distance sufficient to freely accommodate between them the roller-member 10 before referred to and which extend at an angle to the end-plates or end-walls 13, 14 thereof. The free ends of the side-arms 20 and 21 are turned inwardly toward each other to respectively provide

bearing-fingers 22 and 23 respectively freely fitting into the bearing-cuffs 15 and 16 of the roller-member 10.

In addition to the yoke 18, the handle-unit 11 includes a substantially-straight handle-reach 24 and a bracket-arm 25 extending over the roller-member 10 and provided at its free end with a loop 26. The handle-reach 24 and bracket-arm 25 are preferably integral with each other and at their juncture they are spot-welded as at 27 or otherwise rigidly secured to the cross-reach 19 of the yoke 18.

Suspended from the loop 26 of the bracket-arm 25 is a bell 28 or other suitable device for producing sound. As shown, the bell 28 is provided with a clapper 29 which is adapted in the ordinary manner of bells to swing from side to side.

Preferably, the parts 12, 13 and 14 are formed from thin sheet metal to thus more readily produce sound, while the parts 18, 24 and 25 are preferably formed from relatively-heavy metal wire or the like.

Preferably and as shown, the substantially-straight handle-reach 24 of the handle-unit 11 is covered by a tubular body 30 of plastic material such, for instance, as cellulose acetate, rubber, or vinylidene chloride.

The sleeve or tube 30 is interposed between the spot-weld 27 and the inner end of a handle-like terminal 31 fitted over the extreme outer end of the handle-reach 24 and cemented or otherwise secured thereto. The said sleeve or tube 30 serves to effectively conceal kinks and bends in the handle-reach 24 after the same has been bent or distorted by children and substantially restored to normal straightness.

Now when a child grasps the terminal 31 and pushes the toy forwardly, the roller-member 10 will gyrate or wobble between the positions indicated by full lines in Fig. 1 and the positions shown by broken lines in the same figure. The edges of the respective end-plates 13 and 14 will alternately strike the side-arms 20 and 21, thereby causing a sound twice for each revolution of the said roller-member.

As the toy is moved forwardly as above described, not only will the roller-member 10 gyrate in the manner indicated in Fig. 1, but the yoke 18 will have its respective opposite ends alternately raised and lowered in the manner indicated in Fig. 3. This movement of the yoke 18 will cause the bracket-arm 25 to swing from side to side between the extremes indicated by full lines in Fig. 3 and the broken lines in the same figure. This motion will cause the sounding of the bell 28 also twice for each revolution of the roller-member 10.

From the foregoing it will be seen that by mounting a yoke eccentrically with respect to a roller-member rather than coaxially with respect thereto, not only is the said roller-member caused to gyrate or wobble but the said roller-member may be caused to strike the arms of the yoke in the manner above described and thus produce a sound which is amusing to children.

Furthermore, by connecting the yoke 18 or its equivalent in such manner that at least one of its ends is eccentrically connected to the roller-member 10 or its equivalent, the bell 28 or other sounding device is caused to sound, thus dispensing with costly and troublesome mechanisms.

The invention may be carried out in other

specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A rollable sound-producing toy, including in combination: a roller-member having opposite end-portions of substantially-circular form in cross section, each of the said end-portions having one of two complemental bearings and one at least of the said bearing being eccentric; and a handle-unit having a yoke-portion straddling the said roller-member in angular relation to the ends thereof and being provided with two bearing-portions respectively engaging with the bearings of the end-portions of the said roller-member, the said roller-member and the said yoke-portion being proportioned and arranged to cause the said roller-member to strike the said yoke-portion as the roller-member and yoke-portion are caused to gyrate with respect to each other by the said eccentric connection as the roller-member is rolled along a surface by means of the said handle-unit.

2. A rollable sound-producing toy, including in combination: a roller-member of hollow drum-like form and having opposite end-walls, each of the said end-walls having one of two complemental bearings and one at least of the said bearings being eccentric; and a handle-unit having a yoke-portion straddling the said roller-member in angular relation to the ends thereof and being provided with two bearing-portions respectively engaging with the bearings of the end-walls of the said hollow roller-member, the said roller-member and the said yoke-portion being proportioned and arranged to cause the peripheries of the opposite end-walls of said roller-member to strike the said yoke-portion as the roller-member and yoke-portion are caused to gyrate with respect to each other by the said eccentric connection as the roller-member is rolled along a surface by means of the said handle-unit.

3. A rollable sound-producing toy, including in combination: a roller-member having opposite end-portions of substantially-circular form in cross section, each of the said end-portions having one of two complemental bearings and one at least of the said bearings being eccentric; and a handle-unit having a yoke-portion straddling the said roller-member and provided with opposite side-arms each having a bearing-portion respectively engaging with the bearings of the end-walls of the said roller-member, the said roller-member and the side-arms of the said yoke portion being proportioned and arranged to cause the said roller-member to strike a side-arm of the said yoke-portion as the said roller-member and yoke-portion are caused to gyrate with respect to each other by the said eccentric connection as the roller-member is rolled along a surface by means of the said handle-unit.

4. A rollable sound-producing toy, including in combination: a roller-member of hollow drum-like form and having opposite end-walls, each of the said end-walls having one of two complemental bearings and one at least of the said bearings being eccentric; and a handle-unit having a yoke-portion straddling the said roller-member and provided with opposite side-arms each having a bearing-portion respectively en-

gaging with the bearings of the end-walls of the said roller-member, the said roller-member and the side-arms of the said yoke-portion being proportioned and arranged to cause the said roller-member to strike a side-arm of the said yoke-portion as the hollow roller-member and yoke-portion are caused to gyrate with respect to each other by the said eccentric connection as the roller-member is rolled along a surface by means of the said handle-unit.

5. A rollable sound-producing toy, including in combination: a roller-member having opposite end-portions of substantially-circular form in cross section, each of the said end-portions having one of two complementary eccentric bearings; and a handle-unit having a yoke-portion straddling the said roller-member in angular relation to the ends thereof and being provided with two bearing-portions respectively engaging with the eccentric bearings of the end-portions of the said roller-member, the said roller-member and the said yoke-member being proportioned and arranged to cause the said roller-member to strike the said yoke-portion as the roller-member and yoke-portion are caused to gyrate with respect to each other by the said double eccentric connection as the roller-member is rolled along a surface by means of the said handle-unit.

6. A rollable sound-producing toy, including in combination: a hollow roller-member of drum-like form and having opposite end-walls, each

of the said end-walls having one of two complementary eccentric bearings; and a handle-unit having a yoke-portion straddling the said hollow roller-member in angular relation to the ends thereof and being provided with two bearing-portions respectively engaging with the eccentric bearings of the end-portions of the said roller-member, the said roller-member and the said yoke-member being proportioned and arranged to cause the said roller-member to strike the said yoke-portion as the roller-member and yoke-portion are caused to gyrate with respect to each other by the said double eccentric connection as the roller-member is rolled along a surface by means of the said handle-unit.
